CLAIM

The ornamental design of the floor mat, as shown and described.

DESCRIPTION

FIG. 1 is a top perspective view of the floor mat of the present invention;

FIG. 2 is a bottom perspective view thereof;

FIG. 3 is a top plan view thereof;

FIG. 4 is an enlarged view of a portion of FIG. 3;

FIG. 5 is a bottom plan view thereof; and,

FIG. 6 is an enlarged view of a portion of FIG. 5.

The broken line showing of the lines on the floor mat is included for the purpose of illustrating environment and forms no part of the claimed design.
